CLAIM

The ornamental design for a floor cleaning machine, as shown and described.

DESCRIPTION

FIG. 1 is a front perspective view of the floor cleaning machine according to one embodiment;

FIG. 2 is a front elevation view of the floor cleaning machine of FIG. 1;

FIG. 3 is a rear elevation view of the floor cleaning machine of FIG. 1;

FIG. 4 is a right elevation view of the floor cleaning machine of FIG. 1;

FIG. 5 is a left elevation view of the floor cleaning machine of FIG. 1;

FIG. 6 is a top plan view of the floor cleaning machine of FIG. 1;

FIG. 7 is a bottom plan view of the floor cleaning machine of FIG. 1;

FIG. 8 is a perspective view of the floor cleaning machine according to a second embodiment;

FIG. 9 is a front elevation view of the floor cleaning machine of FIG. 1;

FIG. 10 is a rear elevation view of the floor cleaning machine of FIG. 1;

FIG. 11 is a right elevation view of the floor cleaning machine of FIG. 1;

FIG. 12 is a left elevation view of the floor cleaning machine of FIG. 1;

FIG. 13 is a top plan view of the floor cleaning machine of FIG. 1; and,

FIG. 14 is a bottom plan view of the floor cleaning machine of FIG. 1.

(Continued)

The dotted lines showing portions of the floor cleaning machine depict environment and form no part of the claimed design.

1 Claim, 14 Drawing Sheets
